(57) **ABSTRACT**

The image forming apparatus includes an image carrier, a charging unit, an exposure unit, a developing unit, a transfer unit, a cleaning blade, and a controller. The controller detects printing-coverage rates on a basis of plural areas divided in the longitudinal direction of the image carrier. Upon occurrence of a difference exceeding a specified threshold value among the coverage rates of the plural areas, the controller executes, for a duration of specified aging time, aging process in which the image carrier is driven into rotation in its charged state.

IMAGE FORMING APPARATUS

INCORPORATION BY REFERENCE

This application is based on and claims the benefit of priority from Japanese Patent Application No. 2023-097847 filed on Jun. 14, 2023, the contents of which are hereby incorporated by reference.

BACKGROUND

The present disclosure relates to an image forming apparatus using electrophotographic process and, more particularly, to uniformization of surface potential of an image carrier.

A conventional image forming apparatus of electrophotographic system includes an image carrier (photosensitive member), a charging unit, an LSU, a developing unit, and a fixing unit. Upon input of an instruction for image formation, the cylindrical-shaped image carrier is rotated to make a surface of the image carrier electrically charged by the charging unit. On the charged surface of the image carrier, an electrostatic latent image is formed by exposure of the LSU, and developed into a toner image by the developing unit. The toner image formed on the surface of the image carrier is transferred onto a paper sheet via an intermediate transfer belt, and thereafter an image is fixed on the sheet by the fixing unit. Toner remaining on the image carrier is scraped away by a blade.

SUMMARY

The image forming apparatus of the present disclosure includes an image carrier, a charging unit, an exposure unit, a developing unit, a transfer unit, a cleaning blade, and a controller. The image carrier, having a photosensitive layer on its surface, is driven into rotation, and its surface is electrically charged by the charging unit. The exposure unit exposes to light the charged surface of the image carrier to form an electrostatic latent image, and the developing unit develops the electrostatic latent image into a toner image. The transfer unit transfers the toner image on the image carrier to a recording medium to form an image thereon. The cleaning blade scrapes away toner remaining on the image carrier. The controller detects coverage rates on a basis of plural areas divided in a longitudinal direction of the image carrier. Upon occurrence of a difference exceeding a specified threshold value among the coverage rates of the plural areas, the controller executes, for a duration of specified aging time, aging process in which the image carrier is driven into rotation in its charged state.

These and other features of the present disclosure, and specific benefits obtained according to the present disclosure, will become more apparent from the description of an embodiment which follows.

BRIEF DESCRIPTION OF THE DRAWINGS

FIG. 1 is a schematic diagram showing an internal configuration of an image forming apparatus according to one embodiment of the present disclosure;

FIG. 2 is an enlarged view of around an image forming part in FIG. 1;

FIG. 3 is a block diagram showing an example of control paths in the image forming apparatus of the embodiment of the present disclosure;

FIG. 4 is a chart showing coverage-rate-based differences in surface potential of a photosensitive drum; and

FIG. 5 is a flowchart showing printing operation including aging process in the image forming apparatus according to the embodiment of the present disclosure.

DETAILED DESCRIPTION

Hereinafter, an embodiment of the present disclosure will be described with reference to the accompanying drawings. First mentioned is a problem of conventional image forming apparatuses.

In a conventional image forming apparatus, when its image carrier is formed from positively-charged organic photoconductor, the image carrier would undergo generation of carriers on a photosensitive layer by triboelectrification due to frictional force against a blade. In this case, as a characteristic concerned, the stronger the frictional force is, the more the carriers increase on the photosensitive layer. On the other hand, the frictional force between the image carrier and the blade becomes stronger with increasing toner quantity on the image carrier. For this reason, given differences in lengthwise coverage rate (printing-coverage rate) of the image carrier, there arise differences in generated carrier quantity between larger and smaller portions of intervening toner. In this state, electrically charging the image carrier by the charging unit would cause differences in surface potential of the image carrier to be generated in response to generated carrier quantities, leading to appearance of bands and stripes. Thus, there would be a problem that stable images are unobtainable.

Accordingly, in view of the above-described problem, an object of the present disclosure is to provide an image forming apparatus capable of maintaining the surface potential of the image carrier uniform and obtaining stable images.

FIG. 1 is a schematic diagram showing a configuration of an image forming apparatus 100 according to one embodiment of the disclosure. FIG. 2 is an enlarged view of around an image forming part Pa in FIG. 1.

The image forming apparatus 100 shown in FIG. 1 is a so-called tandem-type color printer having the following configuration. In a housing of the image forming apparatus 100, four image forming parts Pa, Pb, Pc, Pd are arrayed in this order starting from an upstream side (left side in FIG. 1) of a sheet conveyance direction. These image forming parts Pa to Pd are provided in correspondence to images of different four colors (yellow, cyan, magenta and black), respectively, so as to form images of yellow, cyan, magenta and black sequentially by processes of charging, exposure, development and transfer.

Photosensitive drums 1a, 1b, 1c, 1d (image carriers) for carrying individual-color visible images (toner images) are set in those image forming parts Pa to Pd, respectively. The photosensitive drums 1a to 1d, which are formed from positively-charged mono-layer organic photoconductor, each have a photosensitive layer on their surface. Further in FIG. 1, an intermediate transfer belt 8 that is rotated counterclockwise is provided in adjacency to the image forming parts Pa to Pd. Toner images formed on those photosensitive drums 1a to 1d are transferred sequentially onto the intermediate transfer belt 8 that moves while keeping in contact with the photosensitive drums 1a to 1d.

Thereafter, the toner images on the intermediate transfer belt 8 are transferred by a secondary transfer roller 9 onto a paper sheet S which is an example of recording medium. The sheet S, after having the toner images fixed thereon in

the fixing unit 13, is discharged from within the image forming apparatus 100. With the photosensitive drums 1a to 1d kept rotated clockwise in FIG. 1, image formation process for the photosensitive drums 1a to 1d is executed.

Sheets S onto which toner images are to be transferred are contained in a sheet cassette 16 set in lower portion of the housing of the image forming apparatus 100. A sheet S is conveyed via a feed roller 12a and a registration roller pair 12b to the secondary transfer roller 9. A seamless belt is mostly used as the intermediate transfer belt 8.

Next, the image forming parts Pa to Pd will be explained. A detailed description about the image forming part Pa will be given below because the image forming parts Pb to Pd are identical in basic configuration to the image forming part Pa, with description of the image forming parts Pb to Pd omitted. As shown in FIG. 2, a charging unit 2a, a developing unit 3a, and a cleaning unit 7a are disposed around the photosensitive drum 1a and along a drum rotational direction (clockwise direction in FIG. 2), while a primary transfer roller 6a is placed so as to pinch the intermediate transfer belt 8 against the photosensitive drum 1a. Further, a belt cleaning unit 19 is placed on an upstream side of the photosensitive drum 1a in the rotational direction of the intermediate transfer belt 8. The belt cleaning unit 19 is opposed to a tension roller 11 with the intermediate transfer belt 8 pinched therebetween.

An exposure unit 5 is placed under the image forming parts Pa to Pd. The exposure unit 5, which is implemented by a laser scanning unit (LSU), includes a light source such as a semiconductor laser, a scanning mirror such as a polygon mirror, and optical components such as lenses. Light beams emitted from the light source scan the photosensitive drums 1a to 1d, respectively.

Next, image formation procedure in the image forming apparatus 100 is explained. Upon input of a start of image formation by a user, the photosensitive drums 1a to 1d are driven into rotation by a main motor 61 (see FIG. 3). Surfaces of the rotating photosensitive drums 1a to 1d are electrically charged uniformly by charging rollers 20 of the charging units 2a to 2d, respectively. Subsequently, light beams (laser light) emitted from the exposure unit 5 scan and illuminate the surfaces of the photosensitive drums 1a to 1d. As a result, electrostatic latent images with their charging level attenuated are formed on the photosensitive drums 1a to 1d in response to image signals, respectively.

Individual-color toner of yellow, cyan, magenta and black is filled to a specified quantity in each of the developing units 3a to 3d. In addition, when toner rate in two-component developer filled in each of the developing units 3a to 3d has declined below a predetermined point because of later-described formation of toner images, toner is refilled from toner containers 4a to 4d into the developing units 3a to 3d, respectively. This toner in the developer is fed and electrostatically deposited onto the photosensitive drums 1a to 1d by developing rollers 21 of the developing units 3a to 3d, respectively. As a result, toner images responsive to the electrostatic latent images formed by exposure of the exposure unit 5 are formed.

Then, by primary transfer rollers 6a to 6d, electric fields are imparted at a specified transfer voltage between the primary transfer rollers 6a to 6d and the photosensitive drums 1a to 1d, respectively. As a result, toner images of yellow, cyan, magenta and black on the photosensitive drums 1a to 1d are primarily transferred onto the intermediate transfer belt 8. These four-color images are formed with a positional relationship predetermined for the purpose of specified full-color image formation. Thereafter, toner

remaining on the surfaces of the photosensitive drums 1a to 1d is removed by scraping with cleaning blades 22 and scraping rollers 23, respectively. Thus, the photosensitive drums 1a to 1d can be set ready for subsequent formation of new electrostatic latent images.

As a driving roller 10 is rotated by a belt driving motor 63 (see FIG. 3), the intermediate transfer belt 8 starts to be rotated counterclockwise. The sheet S is conveyed at a specified timing from the registration roller pair 12b to the secondary transfer roller 9 provided in adjacency to the intermediate transfer belt 8. A full-color toner image is transferred onto the sheet S by the secondary transfer roller 9. Therefore, the primary transfer rollers 6a to 6d, the intermediate transfer belt 8, and the secondary transfer roller 9 constitute a transfer unit which transfers toner images on the photosensitive drums 1a to 1d to a recording medium (sheet S).

The sheet S onto which a toner image has been transferred is conveyed to the fixing unit 13. Toner remaining on the surface of the intermediate transfer belt 8 is removed by the belt cleaning unit 19. The sheet S conveyed to the fixing unit 13 is heated and pressurized by a fixing roller pair 13a so that the toner image is fixed on the sheet surface, with a result that a specified full-color image is formed. The sheet S with the full-color image formed thereon is assorted in terms of conveyance direction depending on involvement or not of double-sided printing by a branching unit 14 having branches into plural directions. The sheet S, as it is or after fed to a double-sided conveyance path 18 and subjected to double-sided printing, is discharged onto a discharge tray 17 by a discharge roller pair 15.

FIG. 3 is a block diagram showing an example of control paths in the image forming apparatus 100 of this embodiment. In addition, since various types of control over individual units are performed for use of the image forming apparatus 100, control paths over the whole image forming apparatus 100 become complicated ones. Therefore, portions of the control paths necessary for embodiment of the present disclosure will be described emphatically.

A controller 90 includes a CPU 91 as a central processing unit, ROM 92 which is a read-only storage unit, RAM 93 which is a readable/writable storage unit, a temporary storage unit 94 for temporarily storing image data or the like, a counter 95, and a plurality (two in this case) of I/F (Interface) units 96 for transmitting control signals to units in the image forming apparatus 100 or for receiving input signals from an operation part 80. In addition, the controller 90 is placeable at an arbitrary place inside the housing of the image forming apparatus 100.

Contained in the ROM 92 are control programs for the image forming apparatus 100 as well as numerical values or the like necessary for control, and data that are invariable during use of the image forming apparatus 100, or the like. Stored in the RAM 93 are necessary data generated in the course of control of the image forming apparatus 100, as well as data temporarily needed for control of the image forming apparatus 100, or the like. The counter 95 cumulates and counts number of printed sheets.

The controller 90 transmits control signals from the CPU 91 through the I/F 96 to individual units of the image forming apparatus 100. Also, signals indicative of individual units' state or input signals are transmitted from the individual units through the I/F 96 to the CPU 91. The individual units to be controlled by the controller 90 include, for example, the image forming parts Pa to Pd, the main motor 61, the belt driving motor 63, an image input part 70, a voltage control circuit 71, the operation part 80, and the like.

The image input part 70 is a reception part for receiving image data transmitted from a personal computer or other device to the image forming apparatus 100. An image signal inputted from the image input part 70 is converted into a digital signal and then sent out to the temporary storage unit 94.

The voltage control circuit 71 is connected to a charging voltage power supply 72, a developing voltage power supply 73 and a transfer voltage power supply 74, and capable of activating these power supplies with output signals derived from the controller 90. By way of a control signal from the voltage control circuit 71, the charging voltage power supply 72 applies a specified charging voltage to the charging rollers 20 within the charging units 2a to 2d, respectively. By way of a control signal from the voltage control circuit 71, the developing voltage power supply 73 applies a specified developing voltage, in which AC voltage has been superimposed on DC voltage, to the developing rollers 21 within the developing units 3a to 3d, respectively. By way of a control signal from the voltage control circuit 71, the transfer voltage power supply 74 applies specified transfer voltages to the primary transfer rollers 6a to 6d and the secondary transfer roller 9, respectively.

A liquid crystal display 81, and an LED 82 indicative of various statuses are provided in the operation part 80. A user operates a stop/clear button of the operation part 80 to stop image formation, and operates a reset button to put various settings of the image forming apparatus 100 to default statuses. The liquid crystal display 81 indicates a status of the image forming apparatus 100, or displays an image-formation status or a number of printed sheets. The various settings are implemented from a personal-computer printer driver.

Here is described aging process of the image forming apparatus 100. FIG. 4 is a chart showing variations in surface potential V0 of the photosensitive drums 1a to 1d versus number of printed sheets in the image forming apparatus. The vertical axis represents surface potential V0 (in unit of V), and the horizontal axis represents number of printed sheets (in unit of sheets). In the figure, solid line represents a case with a coverage rate of 0%, and broken line represents a case with a coverage rate of 100%.

With higher coverage rates, larger quantities of toner tend to intervene between the photosensitive drums 1a to 1d and the cleaning blades 22, respectively, involving larger frictional force therebetween. Hence, increased carriers result which are generated at the photosensitive layers due to triboelectrification, so that the surface potential V0 of the photosensitive drums 1a to 1d becomes higher than those in cases of lower coverage rates as shown in FIG. 4. Consequently, involvement of differences in coverage rate in a longitudinal direction (rotational axis direction) of the photosensitive drums 1a to 1d would cause differences in quantity of generated carriers in the longitudinal direction. In this state, charging the photosensitive drums 1a to 1d causes differences in surface potential in response to the quantity of generated carriers.

For this reason, the aging process is executed at a specified timing with a view to uniformizing the surface potential of the photosensitive drums 1a to 1d.

FIG. 5 is a flowchart showing printing operation including the aging process in the image forming apparatus 100. As an instruction for printing is issued from the image input part 70 (see FIG. 3), printing is started at step S11. At step S12, count of coverage rates Pi for individual areas that are previously divided along the longitudinal direction (axial direction) of the photosensitive drums 1a to 1d is started by

the CPU 91. The area-basis coverage rates Pi are stored in the RAM 93 on a print-page basis.

At step S13, it is decided whether or not the print job has been completed. Given no completion of the print job, steps S12 and S13 are repeated; given a completion, processing moves on to step S14. At step S14, average coverage rates Pi_ave (%) resulting from averaging coverage rates Pi of individual printed pages are derived on the area basis by the CPU 91, and stored in the RAM 93.

At step S15, whether or not a difference Δ Pi_ave (% pt) between maximum and minimum values of the average coverage rates Pi_ave is equal to or more than a specified threshold value Da. When the difference Δ Pi_ave in average coverage rate is equal to or more than the specified threshold value Da, the processing flow moves on to step S16; when the difference is less than the threshold value Da, the processing flow is ended.

At step S16, the aging process in which the photosensitive drums 1a to 1d are rotationally driven in their charged state is executed for a duration of a specified aging time Ta. At step S17, coverage rates Pi and average coverage rates Pi_ave stored in the RAM 93 are reset, where the processing is ended.

The threshold value Da and the aging time Ta are determined by preliminarily executing tests. It is also possible to provide a plurality of threshold values and a plurality of aging times corresponding to those threshold values. For example, a threshold value Db may be provided in addition to the threshold value Da, where given a difference in average coverage rate beyond the threshold value Da, the aging process is executed with the aging time Ta; and given a difference beyond the threshold value Db, the aging process is executed with an aging time Tb. Providing a plurality of threshold values allows unnecessary aging process to be omitted, making it possible to shorten the image formation time. Three or more threshold values and aging times corresponding to those may also be provided.

Table 1 shows test results for determining threshold values and aging times. Test samples were given by four kinds of documents of which differences Δ Pi_ave between maximum and minimum values of average coverage rates Pi_ave are equal to 10% pt, 30% pt, 50% pt, and 100% pt. Each document is composed of 1,000 sheets of A4-size paper.

As test conditions, after each document of 1,000 sheets were continuously printed, the photosensitive drums 1a to 1d were electrically charged and the aging process was executed, followed by checking a state of potential-variation occurrence. Tests were carried out for aging times Ta of 0 sec., 0.3 sec., 0.6 sec., 0.9 sec., and 1.2 sec. per sheet. That is, aging times Ta for each document of 1,000 sheets were 0 min., 5 min., 10 min., 15 min., and 20 min.

TABLE 1

AGING TIME (SEC/SHEET)	0	0.3	0.6	0.9	1.2
AVERAGE COVERAGE	10	○	○	○	○
RATE DIFFERENCE	30	○	○	○	○
Δ Pi_ave	50	×	×	×	○
	100	×	×	×	○

According to Table 1, given that average-coverage-rate differences Δ Pi_ave $\leq$ 30% pt, there occurred no potential variations. Given that the average-coverage-rate difference Δ Pi_ave = 50% pt, there occurred potential variations under a condition that the aging time Ta was 0.6 sec./sheet or less, whereas no potential variations occurred under a condition

that the aging time T_a was 0.9 sec./sheet. Further, given that the average-coverage-rate difference $\Delta P_{ave} = 100\% \text{ pt}$, there occurred potential variations under a condition that the aging time T_a was 0.9 sec./sheet or less, whereas no potential variations occurred under a condition that the aging time T_a was 1.2 sec./sheet.

From these results, the present embodiment is based on the assumption that the threshold value $D_a = 30\% \text{ pt}$, while the aging time T_a per sheet for more than the threshold value D_a is set to 0.9 sec. Further, it is also assumed that the threshold value $D_b = 50\% \text{ pt}$, while the aging time T_b per sheet for more than the threshold value D_b is set to 1.2 sec.

According to this embodiment, since the aging process is executed for a specified aging time T_a when a difference exceeding the specified threshold value D_a has occurred to coverage rates P_i of plural areas, it becomes implementable to maintain the surface potential of the photosensitive drums $1a$ to $1d$ (image carriers) uniform and thus obtain stable images.

Also, an average coverage rate P_{ave} resulting from averaging coverage rates P_i on the area basis is derived upon a job completion, where given that a difference ΔP_{ave} between maximum and minimum values of area-basis average coverage rates has exceeded the threshold values D_a and D_b , the aging process is executed. As a consequence, it becomes easily implementable to execute the aging process based on differences among coverage rates P_i of plural areas.

Further, with a plurality of threshold values D_a and D_b provided, there is a difference between the aging time T_a corresponding to cases of more than the threshold value D_a and the aging time T_b corresponding to cases of more than the threshold value D_b . As a consequence, it becomes implementable to omit unnecessary aging process, allowing the image formation time to be shortened.

The present disclosure is not limited to the above-described embodiment and may otherwise be changed and modified in various ways without departing from the gist of the present disclosure. In the above embodiment, the threshold values D_a and D_b at which the aging process is started are determined depending on a difference between maximum and minimum values of average coverage rates resulting from averaging area-basis coverage rates for each job. However, other threshold values are also usable.

For example, the aging process may also be executed when a maximum ratio of average coverage rates between areas has exceeded a threshold value. Further, since the number of printed characters varies correspondingly with varying coverage rate, the aging process may be executed when a difference between maximum and minimum values of printed-character total numbers on an area basis has exceeded a threshold value. That is, when a difference in area-basis coverage rate in the longitudinal direction of the photosensitive drums $1a$ to $1d$ has exceeded a specified threshold value, the aging process for a specified aging time is executed.

Although the aging process is executed depending on a decision whether or not the aging process is executed upon a job completion in the above embodiment, the aging process may also be executed at other timing. For example, the aging process may also be executed depending on a decision, each time a plurality of jobs have been completed, as to whether or not the aging process is executed. The aging process may be executed at a job start on a basis of a preceding-time job.

Without being limited to such tandem-type color printers as shown in FIG. 1, the present disclosure is applicable to various types of image forming apparatuses such as mono-

chromatic printers or monochromatic copiers, digital multifunction peripherals, color copiers or color multifunction peripherals, and so on.

In this disclosure, when a difference among coverage rates of plural areas has exceeded a threshold value, the aging process is executed for a specified aging time. Thus, it becomes implementable to maintain surface potential of the image carriers uniform and therefore obtain stable images.

The present disclosure is applicable to image forming apparatuses using electrophotographic process.

What is claimed is:

1. An image forming apparatus comprising:
an image carrier which has a photosensitive layer on its surface and which is driven into rotation;
a charging unit for electrically charging the surface of the image carrier;
an exposure unit for exposing to light the surface of the image carrier electrically charged by the charging unit to form an electrostatic latent image;
a developing unit for developing the electrostatic latent image into a toner image;
a transfer unit for transferring the toner image to a recording medium;
a cleaning blade for scraping away toner remaining on the image carrier; and
a controller, wherein
the controller detects coverage rates on a basis of plural areas divided in a longitudinal direction of the image carrier, derives area-basis average coverage rates resulting from averaging the area-basis coverage rates, and if a difference between maximum and minimum values of the area-basis average coverage rates has exceeded a specified threshold value, the controller executes, for a duration of specified aging time, aging process in which the image carrier is driven into rotation in its charged state, and
the controller decides whether or not to perform the aging process based solely on the difference and the threshold value.

2. The image forming apparatus according to claim 1, wherein
the threshold value comprises a plurality of threshold values, and the aging time varies so as to correspond to the individual threshold values that are exceeded by the difference of the average coverage rates.

3. The image forming apparatus according to claim 2, wherein
the image carrier is a positively-charged organic photosensitive member.

4. The image forming apparatus according to claim 1, wherein
the image carrier is a positively-charged organic photosensitive member.

5. An image forming apparatus comprising:
an image carrier which has a photosensitive layer on its surface and which is driven into rotation;
a charging unit for electrically charging the surface of the image carrier;
an exposure unit for exposing to light the surface of the image carrier electrically charged by the charging unit to form an electrostatic latent image;
a developing unit for developing the electrostatic latent image into a toner image;
a transfer unit for transferring the toner image to a recording medium;
a cleaning blade for scraping away toner remaining on the image carrier; and

a controller, wherein
the controller detects coverage rates on a basis of plural areas divided in a longitudinal direction of the image carrier, derives area-basis average coverage rates resulting from averaging the area-basis coverage rates, and if a maximum value of a ratio of the area-basis average coverage rates has exceeded a specified threshold value, the controller executes, for a duration of specified aging time, aging process in which the image carrier is driven into rotation in its charged state, and the controller decides whether or not to perform the aging process based solely on the ratio and the threshold value.

6. The image forming apparatus according to claim 5, wherein
the threshold value comprises a plurality of threshold values, and the aging time varies so as to correspond to the individual threshold values that are exceeded by the difference of the average coverage rates.

7. The image forming apparatus according to claim 5, wherein
the image carrier is a positively-charged organic photo-sensitive member.

8. An image forming apparatus comprising:
an image carrier which has a photosensitive layer on its surface and which is driven into rotation;
a charging unit for electrically charging the surface of the image carrier;
an exposure unit for exposing to light the surface of the image carrier electrically charged by the charging unit to form an electrostatic latent image;

a developing unit for developing the electrostatic latent image into a toner image;

a transfer unit for transferring the toner image to a recording medium;

a cleaning blade for scraping away toner remaining on the image carrier; and

a controller, wherein

if a difference between maximum and minimum values of printed-character total numbers on a basis of plural areas divided in a longitudinal direction of the image carrier has exceeded a specified threshold value, the controller executes, for a duration of specified aging time, aging process in which the image carrier is driven into rotation in its charged state, and

the controller decides whether or not to perform the aging process based solely on the difference and the threshold value.

9. The image forming apparatus according to claim 8, wherein
the threshold value comprises a plurality of threshold values, and the aging time varies so as to correspond to the individual threshold values that are exceeded by the difference of the average coverage rates.

10. The image forming apparatus according to claim 8, wherein
the image carrier is a positively-charged organic photo-sensitive member.
